REFRIGERATING APPARATUS

William W. Watt, Dayton, Ohio, assignor to General Motors Corporation, Dayton, Ohio, a corporation of Delaware

Application October 24, 1934, Serial No. 749,788

8 Claims. (Cl. 62—126)

The present invention relates to refrigerating apparatus and particularly to an evaporator therefor.

An object of the present invention is to provide an improved evaporator for quickly freezing substances placed in thermal association therewith.

Another object of the present invention is to provide an improved evaporator having a maximum of cooling surface in direct thermal contact with walls of containers or the like placed in or on the evaporator and adapted to contain a substance to be congealed or frozen.

Another object of the invention is to provide an improved evaporator for installation in a refrigerator cabinet of the so-called top opening type which evaporator will efficiently cool the interior of the cabinet while at the same time quickly chilling substances to be congealed or frozen.

A more specific object of the invention is to provide an evaporator with a plurality of compartments for the reception of cups or the like receptacles, containing a substance to be congealed or frozen, and constructing the compartments so that the walls thereof will conform to the contour of the walls of the cups to thereby permit substantially all of the walls of the cups to be in direct thermal association with the compartment walls and consequently refrigerant circulated through the evaporator.

In carrying out the foregoing object it is a still further object of the invention to provide means whereby a receptacle or cup located within a compartment formed in an evaporator, of the type herein disclosed, can be quickly and readily removed.

Further objects and advantages of the present invention will be apparent from the following description, reference being had to the accompanying drawings, wherein a preferred form of the present invention is clearly shown.

In the drawings:

Fig. 1 discloses a refrigerator cabinet of the type having a plurality of stationary walls and a movable top wall or door cooperating with the stationary walls and affording access to a compartment formed by the walls within the cabinet;

Fig. 2 is an enlarged cross-sectional view of the cabinet disclosed in Fig. 1 and is taken on lines 2—2 thereof showing my improved evaporator mounted therein;

Fig. 3 is an enlarged fragmentary sectional view of the cabinet taken on line 3—3 of Fig. 2

showing my improved evaporator mounted therein;

Fig. 4 is an enlarged vertical sectional view of the evaporator shown in the cabinet in Fig. 2 and is taken on the line 4—4 thereof;

Fig. 5 is a fragmentary top view of the evaporator shown in Fig. 4;

Fig. 6 is a fragmentary sectional view of the evaporator taken on the lines 6—6 of Fig. 5; and

Fig. 7 is a sectional view of the evaporator taken on the line 7—7 of Fig. 5.

Referring to the drawings, for the purpose of illustrating my invention, I have shown in Fig. 1 thereof a refrigerator cabinet 10 having a door 11 provided on the top thereof and affording access to a food storage compartment 12 (see Figs. 2 and 3) formed by the insulated vertical walls 13 and an insulated bottom wall 14. The lid or door 11 is suitably insulated and forms the top wall of the food storage compartment 12.

Within the food storage compartment 12 of cabinet 10 there is mounted, in any suitable manner, a unitary cooling element or evaporator generally designated by the reference character 20. The evaporator or cooling unit 20 includes a vertically disposed portion for cooling and causing circulation of air in the food storage compartment 12 and also includes a horizontally disposed freezing portion 22. The air cooling portion 21 of evaporator 20 is constructed of sheet metal portions 24 and 25 (see Fig. 4) secured together at certain points and having certain other points thereof spaced apart to provide an upper header or manifold 26 and a lower header or manifold 27 with passageways 28 of any suitable size or configuration connecting the headers 26 and 27 with one another. The freezing portion 22 of the evaporator 20 includes a sheet or a plurality of sheets of metal forming a plurality of walls of a chamber or passage 32. The one wall 33 of the plurality of walls of chamber or passage 32 is secured, in any suitable manner such as by welding, to the upper part of the air cooling portion 21 of the evaporator. This wall 33 of chamber 32 is provided with an opening 34 adjacent one end of the chamber 32 (see Fig. 4) which communicates with the header 26 and which opening also serves as an outlet for refrigerant circulated through the chamber. At the end 35 of the chamber 32, opposite the end 34

adjacent one end of the chamber 32 (see Fig. 4) which communicates with the header 26 and which opening also serves as an outlet for refrigerant circulated through the chamber. At the end 35 of the chamber 32, opposite the end 34

adjacent one end of the chamber 32 (see Fig. 4) which communicates with the header 26 and which opening also serves as an outlet for refrigerant circulated through the chamber. At the end 35 of the chamber 32, opposite the end 34

adjacent one end of the chamber 32 (see Fig. 4) which communicates with the header 26 and which opening also serves as an outlet for refrigerant circulated through the chamber. At the end 35 of the chamber 32, opposite the end 34

adjacent one end of the chamber 32 (see Fig. 4) which communicates with the header 26 and which opening also serves as an outlet for refrigerant circulated through the chamber. At the end 35 of the chamber 32, opposite the end 34

adjacent one end of the chamber 32 (see Fig. 4) which communicates with the header 26 and which opening also serves as an outlet for refrigerant circulated through the chamber. At the end 35 of the chamber 32, opposite the end 34

adjacent one end of the chamber 32 (see Fig. 4) which communicates with the header 26 and which opening also serves as an outlet for refrigerant circulated through the chamber. At the end 35 of the chamber 32, opposite the end 34

The inlet 36 and outlet 37 of the evaporator are connected by suitable pipes or conduits 39 and 41 respectively with a refrigerant liquefying and circulating unit of any conventional and well-known form shown diagrammatically in Fig. 2. Refrigerant may be admitted to the evaporator 20, under the control of any suitable valve or restrictor device 42 (see Figs. 2 and 3), through the inlet 36. Refrigerant flows from the conduit 39 into the chamber 32 through the inlet 36 at the end 35 of the chamber thence through chamber 32 to the opening 34. The refrigerant upon passing through opening 34 flows downwardly through one of the plurality of passageways 28 to header 27 and thence upwardly through a plurality of the passageways 28 to header 26 and through the outlet 37 and conduit 41 back to the refrigerant liquefying unit. It is to be understood that the refrigerating system may be 20 of the so-called dry expansion type or the evaporator may, if desired, be of the flooded type.

The top wall 43 of the freezing portion 22 or of the chamber 32 of evaporator 20 has a plurality of depressions formed therein providing a plurality of compartments 44. These compartments 44 may be of any desired horizontal cross-sectional form and are preferably cylindrical as disclosed and the side walls 46 thereof preferably diverge inwardly from the top to the bottom 30 thereof to form tapering compartments. The bottom wall 47 of the chamber 32 is provided with a plurality of depressions 48 each of which are disposed directly opposite the bottom wall 49 of the compartments 44. The depressions 48 abut 35 against and may be welded or otherwise secured to the walls 49 so as to strengthen the chamber 32 against deformation due to internal pressures. It will be noted that the structure described permits substantially all of the walls of compartments 44 to be exposed to refrigerant flowing 40 through the chamber 32 or to be in direct thermal contact with the refrigerant. The entire evaporator 20 may be plated with a metallic plating applied thereto in any suitable manner or it may be coated with a vitreous enamel coating which 45 may be baked thereon to afford a neat and durable finish.

Each of the plurality of compartments 44 is adapted to receive and support a cup adapted to 50 contain water or any other substance to be congealed or frozen. For this purpose I have shown a cup 51 located in a compartment 44. The cup 51 includes a side wall 52 which is of substantially the same contour as the side walls 46 of compartment 44 or in other words the side wall 52 of the cups 51 diverge inwardly from the top to the bottom of the cup. The cup is adapted to fit 55 into the compartment 44 in such a manner that, when its side wall 52 engages the side wall 46 of the compartment, its bottom wall also engages the bottom wall 49 of the compartment. The cups 51 are slightly taller than the height of compartments 44 and have a flange 53 formed around their top edge. Flange 53 is normally 60 spaced above the surface of the top wall 43 of the chamber 32, when the cup is in position in compartment 44, for the purpose of permitting a key or lever device to be placed between the flange 53 and the wall surface 43 to effect removal of the cup 51 from the compartment 44. I provide a key, lever or the like instrument 55 for 65 prying the cups 51 loose from the walls of compartment 44. The instrument 55 includes two leg portions 56 and a handle portion 57. Leg portions 56 of instrument 55 straddles or surrounds

a portion of the walls 52 of the cups 51 and fit between the flange 53, formed on cup 51, and the top surface of the top wall 43 of chamber 32 in any suitable manner to form a lever for prying the cup upwardly and out of the compartment 44. 5 To remove a cup 51 from the compartment 44 the handle end 57 of instrument 55 may be manually moved upwardly or downwardly, as desired, to loosen and move the cup into the position shown by the dotted lines in Fig. 7. 10

From the foregoing description of the apparatus disclosed it will be apparent that I have provided an improved evaporator and particularly an improved evaporator for installation in the type of refrigerator cabinet herein disclosed. 15 My improved evaporator and the arrangement of the cups therein affords fast freezing of substance contained in the cups. The improved evaporator can be manufactured at a low cost thus rendering same particularly applicable for 20 installation in a cabinet of the type herein shown and described since such cabinet is of the small low cost variety adapted for installation and use in camps, lodges and summer cottages. My improved evaporator and the individual receptacles 25 or cups supported therein permits removal of one or more ice cubes or blocks as desired from the evaporator without disturbing other cups desired to be retained in the evaporator thereby avoiding overloading the refrigerating apparatus connected with the evaporator and rendering operation of the apparatus more economical. 30 This feature of my invention is important in view of the fact that all the cups or ice cubes or blocks in an evaporator of an apparatus of the type disclosed are seldom required to be removed at one time from the evaporator, thus permitting a refrigerant liquefying and circulating unit of small 35 capacity and low manufacturing cost to be employed. 40

While the form of embodiment of the invention as herein disclosed, constitutes a preferred form, it is to be understood that other forms might be adopted, all coming within the scope of the claims which follow. 45

What is claimed is as follows:

1. A refrigerating apparatus comprising in combination, a cabinet having a bottom wall and a plurality of side walls defining a food storage compartment, a movable door on the top of said food storage compartment affording access thereto, an evaporator of a refrigerant circulating system mounted in said compartment, said evaporator including a vertically disposed air cooling portion and a horizontally disposed freezing portion, said freezing portion of said evaporator comprising an elongated substantially flat closed refrigerant expansion chamber having an inlet and an outlet for the circulation of refrigerant therethrough, the top wall of said chamber having a plurality of depressions therein each forming a compartment for the reception of a cup adapted to contain a substance to be congealed or frozen, and substantially all the walls of each of said cup receiving compartments being in intimate thermal contact with refrigerant adapted to be circulated through said expansion chamber. 55

2. A refrigerating apparatus comprising in combination, a cabinet having a bottom wall and a plurality of side walls defining a food storage compartment, a movable door on the top of said food storage compartment affording access thereto, an evaporator of a refrigerant circulating system mounted in said compartment, said evaporator including a vertically disposed air cooling 70 portion and a horizontally disposed freezing portion, said freezing portion of said evaporator comprising an elongated substantially flat closed refrigerant expansion chamber having an inlet and an outlet for the circulation of refrigerant therethrough, the top wall of said chamber having a plurality of depressions therein each forming a compartment for the reception of a cup adapted to contain a substance to be congealed or frozen, and substantially all the walls of each of said cup receiving compartments being in intimate thermal 75 contact with refrigerant adapted to be circulated through said expansion chamber. 85

portion and a horizontally disposed freezing portion, said freezing portion of said evaporator comprising an elongated substantially flat closed refrigerant expansion chamber having an inlet 5 and an outlet for the circulation of refrigerant therethrough, the top wall of said chamber having a plurality of depressions therein each forming a compartment for the reception of a cup adapted to contain a substance to be congealed or frozen, 10 and substantially all the walls of each of said cup receiving compartments being in intimate thermal contact with refrigerant adapted to be circulated through said expansion chamber, the side walls of each of said cup receiving compartments converging inwardly from the top to 15 the bottom of said cup compartments.

3. An evaporator for a refrigerating system comprising walls forming an elongated substantially flat horizontally disposed refrigerant chamber therebetween having an inlet and an outlet for the circulation of refrigerant therethrough, the top wall of said chamber having a plurality of depressions therein each forming a compartment for the reception of a cup, each compartment 20 having a closed bottom wall and side walls extending upwardly therefrom and entirely therearound, a cup removably disposed within each of said compartments and adapted to contain a substance to be congealed or frozen, and the bottom 25 and side walls of each of said compartments being in intimate thermal contact with refrigerant adapted to be circulated through said chamber and with substantially all of the walls of said cups.

4. An evaporator for a refrigerating system 30 comprising walls forming an elongated substantially flat horizontally disposed refrigerant chamber therebetween having an inlet and an outlet for the circulation of refrigerant therethrough, the top wall of said chamber having a plurality 35 of depressions therein each forming a compartment for the reception of a cup, each compartment having a closed bottom wall and side walls extending upwardly therefrom and entirely therearound, a cup removably disposed within each of 40 said compartments and adapted to contain a substance to be congealed or frozen, and the bottom and side walls of each of said compartments being in intimate thermal contact with refrigerant adapted to be circulated through said chamber and with substantially all of the walls of said cups, the side walls of each of said compartments converging inwardly from the top to the bottom of 45 said compartments.

5. An evaporator for a refrigerating system 50 comprising walls forming an elongated substantially flat horizontally disposed refrigerant chamber therebetween having an inlet and an outlet for the circulation of refrigerant therethrough, the top wall of said chamber having a plurality 55 of depressions therein each forming a compartment for the reception of a cup, each compartment having a closed bottom wall and side walls extending upwardly therefrom and entirely therearound, a cup removably disposed within each of 60 said compartments and adapted to contain a substance to be congealed or frozen, the bottom and side walls of each of said compartments being in intimate thermal contact with refrigerant adapted to be circulated through said chamber and with 65 substantially all of the walls of said cups, the side walls of each of said compartments converging inwardly from the top to the bottom of said compartments, and the walls of said cups being of 70 substantially the same contour as the converging compartment walls.

substantially the same contour as the converging compartment walls.

6. A unitary evaporator structure for a refrigerating system comprising a vertically disposed air cooling portion and a horizontally disposed freezing portion, said portions of said evaporator having closed expansion chambers formed therein, means for circulating a refrigerant medium through the expansion chamber of said portions of said evaporator, said freezing portion of said evaporator comprising an elongated substantially flat element having a plurality of depressions formed in its top wall each providing a compartment for the reception of a cup, each compartment having a closed bottom wall and side walls 10 extending upwardly therefrom, a cup removably disposed within each of said compartments and adapted to contain a substance to be congealed or frozen, and the bottom and side walls of each of said compartments being in intimate thermal 15 contact with refrigerant adapted to be circulated through said element and with substantially all of the walls of said cups.

7. A unitary evaporator structure for a refrigerating system comprising a vertically disposed air cooling portion and a horizontally disposed freezing portion, said portions of said evaporator having closed expansion chambers formed therein, means for circulating a refrigerant medium through the expansion chambers of said portions 20 of said evaporator, said freezing portion of said evaporator comprising an elongated substantially flat element having a plurality of depressions formed in its top wall each providing a compartment for the reception of a cup, each compartment having a closed bottom wall and side walls 25 extending upwardly therefrom, a cup removably disposed within each of said compartments and adapted to contain a substance to be congealed or frozen, and the bottom and side walls of each of said compartments being in intimate thermal 30 contact with refrigerant adapted to be circulated through said element and with substantially all of the walls of said cups, the side walls of each of said compartments converging inwardly from the top to the bottom of said compartments.

8. A unitary evaporator structure for a refrigerating system comprising a vertically disposed air cooling portion and a horizontally disposed freezing portion, said portions of said evaporator having closed expansion chambers formed therein, means for circulating a refrigerant medium through the expansion chambers of said portions of said evaporator, said freezing portion of said evaporator comprising an elongated substantially flat element having a plurality of depressions formed in its top wall each providing a compartment for the reception of a cup, each compartment having a closed bottom wall and side walls extending upwardly therefrom, a cup 35 removably disposed within each of said compartments and adapted to contain a substance to be congealed or frozen, the bottom and side walls of each of said compartments being in intimate thermal contact with refrigerant adapted to be circulated through said element and with substantially all of the walls of said cups, the side walls of each of said compartments converging inwardly from the top to the bottom of said compartments, and the walls of said cups being of 40 substantially the same contour as the converging compartment walls.

WILLIAM W. WATT.
